REFILLING VALVE FOR ANIMAL WATER
TROUGHs, WATER FLUSH TANKS AND
SIMILAR USE

Nat Cordis, Silver Lake, Wis.; Gladys S. Cordis, executrix
of said Nat Cordis, deceased, assignor of two-thirds to
Carl F. Jensen, and one-third to Gerald T. Dobie, both
of Crown Industries, Chicago, Ill.

Filed Feb. 26, 1962, Ser. No. 68,963

Term of patent 14 years

(Cl. D91—3)

FIGURE 1 is a top plan view of a refilling valve for animal water troughs, water flush tanks and similar use showing my new design;

FIGURE 2 is a side elevation thereof;

FIGURE 3 is a bottom plan view thereof; and

FIGURES 4 and 5 are end elevations thereof as seen from opposite ends, respectively, of FIGURE 2.

The dominant features of the design reside in the portions shown in full lines.

I claim:

The ornamental design for a refilling valve for animal water troughs, water flush tanks and similar use, as shown.
